CLAIM

The ornamental design for a tire, as shown and described.

DESCRIPTION

FIG. 1 is a perspective view of a tire;

FIG. 2 is an enlarged partial side view thereof; and,

FIG. 3 is a front view of the entire tire thereof.

The remaining three-quarter portions of the tire are repetitive of the illustrated one-quarter portion shown in FIG. 2. The inside and outside views of the tire are the same. The broken lines in FIGS. 1 and 2 illustrate portions of the tire that form no part of the claimed design.
